Attorney.

UNITED STATES PATENT OFFICE.

GEORGE H. HOLTZMAN, OF WICHITA, KANSAS, ASSIGNOR OF ONE-FOURTH TO JAMES J. BULGER, OF WICHITA, KANSAS.

AUTOMOBILE-DOOR HANDLE.

1,314,400.

Specification of Letters Patent. Patented Aug. 26, 1919.

Application filed April 17, 1919. Serial No. 290,810.

To all whom it may concern:

Be it known that I, GEORGE H. HOLTZMAN, a citizen of the United States, residing at Wichita, in the county of Sedgwick and 5 State of Kansas, have invented certain new and useful Improvements in Automobile-Door Handles; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this 15 specification.

My invention relates to an automobile door handle, and has for its object to provide a handle which will serve to prevent the door from being thrown open with such 20 force and to such an extent as to strike against the automobile body or do damage to the door hinges, and which will also serve as an aid to the occupant in leaving or entering the car, and which will also close the 25 door automatically after being opened. To the accomplishment of the foregoing and such other objects as may hereinafter appear the invention consists in the features hereinafter particularly described and then 30 sought to be clearly defined by the claims, reference being had to the accompanying drawing forming a part hereof, and in which,

Figure 1 is a side elevation of a part of an 35 automobile body and door with the handle applied;

Fig. 2 is a horizontal section through the parts illustrated in Fig. 1, and showing in dotted lines the door in its opened position.

40 In the drawing the numeral 1 designates an automobile body of any type of construction, and 2 the hinged door. The handle constituting the present invention is designated by the numeral 3. It consists of a 45 tubular member 4, preferably of metal, and supported from the inside of the door by suitable brackets 5 which in the preferred form have hollow heads 6 into which the ends of the tubular member may be threaded and by which the latter is supported from 50 the door. Within the tubular member 4 is a coil spring 7 one end of which is connected by suitable means, say, by a hook or rod 8

to one of the heads 6, and the other end to a flexible cord or cable 9 which passes 55 through the other bracket head and is formed with a hook or eye 10 which loops into a hook 11 attached to the side of the car as illustrated. Where the cable passes through the head 6 the latter is preferably recessed 60 as indicated at 12 and in the recess is journaled a sheave or guide 13 over which the cable runs. Under the construction described when the door is swung open the pull is on the cable and the spring is distended and put under tension as indicated by the dotted position of the parts in Fig. 2 of the drawing and the door prevented 65 from swinging open with violence or force and from striking against the car body and 70 doing damage to the body or injury to the door hinges. The door when thrown open beyond center may stand in that position, but if opened less than that distance or if given a slight closing impulse will be drawn 75 into its closed position by recoil or retraction of the spring. The tubular member containing the spring also serves as a hand grip for the person leaving or entering the car so as to afford additional safety. To 80 limit the distention of the spring the end thereof next to the cable may be provided with a plate or stop 14 which when the spring reaches the point of distention fixed upon will strike against a shoulder at the 85 end of the tubular member, for instance against a collar 14 which may be threaded into the end of the tubular member, or otherwise provided.

The spring handle attachment may be 90 easily applied to cars already in use without requiring special construction or change in the parts, and constitutes an ornamental as well as useful attachment for automobile car doors. The details of the various parts 95 are susceptible of many changes without departing from the essential features as expressed in some of the claims.

Having described my invention and set forth its merits what I claim is:

100 1. A handle for automobile doors comprising a hand grip for attachment to the door and a retarding and retracting means incased within and connected to the hand grip and to a stationary part other than the 105 door.

2. A handle for automobile doors comprising a tubular member for attachment to the door, a spring within the tubular member, and a cable for connecting the spring to a fixed support.
3. A handle for automobile doors comprising a tubular member for attachment to the door, a coiled spring within the tubular member, a cable connected to the spring, and means for holding attachment of one end of the cable.
4. A handle for automobile doors comprising a tubular member for attachment to the door to serve as a hand grip, a spring within the tubular member, a cable connected to the spring and to a fixed support at

one side of the door, and a sheave carried by the door and over which the cable passes.

5. A handle for automobile doors comprising a tubular member for attachment to the door, a spring within the tubular member, a cable connected to the spring and to a fixed support at one side of the door, and a stop for limiting the distention of the spring.

25 In testimony whereof I affix my signature in presence of two witnesses.

GEORGE H. HOLTZMAN.

Witnesses:

EMMA LEE GREGORY,
J. J. BULGER.
